DESIGN FOR A DRESS ENSEMBLE

Felix Safian, New York, N. Y.

Application March 22, 1937, Serial No. 68,318

Term of patent 3½ years

To all whom it may concern:

Be it known that I, Felix Safian, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a rear view thereof.

Figure 3 is a front view of the dress unit of the dress ensemble shown in Figure 1.

Figure 4 is a rear view thereof.

The salient feature of my design resides in the redingote member of the ensemble, which redingote is characterized by lapels cut in one with the yoke portion in association with the superimposed bands at the yoke and cuff lines, as shown, said bands repeating the dress color.

I claim:

The ornamental design for a dress ensemble, substantially as shown and described.

FELIX SAFIAN.
